UNITED STATES PATENT OFFICE.

ALBERT E. SCHULZ, OF LANSDALE, PENNSYLVANIA, ASSIGNOR TO DEXDALE HOSIERY MILLS, OF LANSDALE, PENNSYLVANIA, A CORPORATION OF PENNSYLVANIA.

KNITTING MACHINE.

Application filed August 9, 1924. Serial No. 731,069.

This invention relates generally to knitting machines, and more particularly to a type wherein the sinkers are released from the actuating means therefor during yarn feeding. This condition is characteristic of the straight or bar type machines ordinarily known as "cotton frames"; and it frequently happens as the result of such release, that the sinkers are accidentally projected through shocks attending the operation of the machine, into the path of the yarn feeds, and either they or said feeds, or both, are bent or broken. Such contingencies, as is known to skilled knitters, entail idleness of the machine until repairs or replacements can be made, these being often very costly.

My object is to obviate the difficulties pointed out; and one convenient and simple way in which this desideratum may be attained will be readily apparent from the detailed description which follows of a typical embodiment of my invention, the appended claims defining those features which I believe to be novel and wholly within the scope of the present improvements.

In the drawings:

Fig. I is an illustration, more or less diagrammatically represented, showing a cross section of a standard straight or bar type of knitting machine, and in association therewith my invention for restraining independent movement of the sinkers, only those parts of the machine essential to a proper understanding of the invention being included.

Figs. II and III are similar views showing the stitch forming instrumentalities in successive positions which they assume during the formation of the fabric loops; and

Fig. IV is a perspective view of a portion of the holding bar of the machine, showing the manner in which I employ the same as a holder for the purposes of my invention.

The knitting machine herein depicted comprises upper and lower sinker bars 1, 2 which are complementarily slotted or grooved as at 3, 4 respectively to jointly support and guide in the interval between them, the sinkers 5, and also the associated dividers 6 that alternate with said sinkers. The sinkers 5 have at their outer ends, the usual acute-angular notches 7 within which the

yarn Y is first engaged and thereafter sunk 55 into the intervals (in the present instance) between adjacent pairs of needles 8 when said sinkers are moved forward as shown in Fig. II. This forward movement is effected through the medium of jacks 9 engaging 60 the thickened or reinforced rear ends of the sinkers 5, said jacks oscillating about a common fixed fulcrum rod 10 under actuation of a slur cock 11 that traverses the machine longitudinally and engages them 65 from behind in the well known manner. Retractive movement of the sinkers 5 is brought about by a catch bar 12 that has a longitudinal slot 13 in its lower face for engaging the upstanding butts 14 at the 70 rear of the sinkers 5. The catch bar 12 has horizontal reciprocatory movement to function as just explained, as well as up and down movement so as to relegate control 75 of the sinkers 5 to the jacks 9 for forward shifting in the manner above described.

The dividers 6 alternating with the sinkers 5, are actuated solely by the catch bar 12, their butts 15 being somewhat longer than those of the sinkers so as to be always engaged within the slot 13 of the bar. The outer ends of the dividers 6 are angularly notched (see Fig. II) to function in precisely the same manner as the sinkers 5, i. e., to sink the yarn Y into the intervals between needles 8 not served by the sinkers 5. At the opposite ends, the dividers 6 are provided as usual with rearwardly projecting tails 16 that cooperate in pairs to afford ways for guiding the rocking movement of 80 the jacks 9.

In operation, the yarn Y is laid by the traversing feed indicated at F. Fig. 1, to the front of the needles 8 and within the angularly recessed channel jointly formed by 85 said needles and the notched outer ends 7 of the sinkers 5 and dividers 6, both of which are at this time in full retracted position as shown in the aforesaid figure. Immediately after the feed F has completed its 90 traverse, the slur cock 11 functions to advance the sinkers 5 (which are then free from the catch bar 12) to the position of Fig. II, with the result that yarn Y is sunk in the intervals between adjacent pairs of 95 needles 8. The dividers 6 are next projected to an extent corresponding to that of the sinkers 5 as a result of horizontal forward 100 105

movement of the catch bar 12 from the full line position of Fig. I, to that of Fig. III. With the yarn Y thus sunk between all the needles 8, the latter are actuated to draw 5 the fabric stitches in the known manner; and immediately when this is accomplished, the catch bar 12 is vertically lowered from the full line position to the dot-and-dash line position of Fig. III, to engage the up- 10 standing butts 14 of the sinkers 5 so as to retract the latter at the same time with the dividers 6 when subsequently shifted rearward to the dot-and-dash line position of Fig. I. The catch bar 12 is finally elevated 15 to the full line position in the latter illustration to release the sinkers 5 in readiness for repetition of the same cycle of operations exactly as before.

Since at certain periods, the sinkers 5 are 20 entirely free or disengaged from the actuating means, i. e. from the catch bar 12 when the same is elevated away from their butts 14 as in Fig. I, they are likely to be displaced through shocks attending operation 25 of the machine inducing forward movement of the jacks 9, which, as will be seen, are top heavy by virtue of the normal outward inclination and therefore tend to thrust the sinkers 5 into the path of the yarn feed F. 30 This contingency I avoid by provision of auxiliary means for restraining any free or independent movement whatever of the sinkers 5 both as regards forward and rearward movement, more particularly during the 35 critical periods when they are disengaged from the catch bar 12. As shown, this means comprises a strip 17 of suitable material, such as felt or leather, adapted at all times to restrain the sinkers 5 by very light friction therewith, without however, interfering 40 with normal operation. As shown this friction strip 17 is sheathed in a metallic channel member 18 with only its lower face exposed. The sheathing 18 insures easy sliding 45 or gravitational movement in a groove 19 formed in the holding bar 20 of the machine (which bar I employ in the present instance as a holder for the strip 17) so that the strip rests freely by its own weight upon 50 the sinkers 5 as shown in the several assembly illustrations. Aside from the groove 19, the holding bar 20 will be observed as of the kind ordinarily associated with knitting machines of this general character, it being provided 55 with the usual edge notches 21 permitting, by cooperation with clamp screws

22, adjustment relative to the upper sinker bar 1 whereto it is secured.

Having thus described my invention, I claim:

1. In a knitting machine, the combination with needles, yarn feeds, sinkers, sinker-actuating means and a holding bar, of a friction device supported by said bar for restraining independent movement of the sinkers relative to the actuating means to prevent their accidental projection into the path of the yarn feeds during yarn feeding.

2. In a knitting machine, the combination with needles, yarn feeds, sinkers, sinker-actuating means and a holding bar, of a friction device gravitationally mounted in the holding bar for restraining free movement of the sinkers during periods of release from the actuating means to prevent their accidental projection into the path of the yarn feeds.

3. In a knitting machine, the combination with needles, yarn feeds, sinkers, sinker-actuating means and a holding bar, of a gravitating device housed in the holding bar adapted to frictionally engage the sinkers to restrain them against independent movement as well as prevent their accidental projection into the path of the yarn feeds during yarn feeding.

4. In a knitting machine, the combination with needles, yarn feeds, sinkers, and sinker actuating means, of means for restraining independent movement of the sinkers relative to the actuating means to prevent their accidental projection into the path of the yarn feeds, the restraining means including a slotted holder, and friction material in the slot of the holder bearing against the sinkers.

5. In a knitting machine, the combination with needles, yarn feeds, sinkers, and sinker actuating means, of auxiliary means for restraining independent movement of the sinkers relative to the actuating means to prevent their accidental projection into the path of the yarn feeds, the restraining means including a slotted holder, and friction material sheathed in metal for sliding guidance in the slot of the holder and resting by its own weight against the sinkers.

In testimony whereof, I have hereunto signed my name at Lansdale, Pa., this 31st day of July, 1924.

ALBERT E. SCHULZ.
